CLAIM

The ornamental design for a controller for dental handpiece, as shown and described.

DESCRIPTION

FIG. 1 is a front elevation of a controller for dental handpiece; FIG. 2 is a rear elevation thereof; FIG. 3 is a right side elevation thereof; FIG. 4 is a left side elevation thereof; FIG. 5 is a top plan view thereof; FIG. 6 is a bottom plan view thereof; and, FIG. 7 is a perspective view from upper right side thereof. Portions of the controller for dental handpiece shown in broken lines form no part of the claimed design.
